UNITED STATES PATENT OFFICE.

THEODOR SULIKX, OF BARBERTON, OHIO.

ROTARY ENGINE.

1,302,877.

Specification of Letters Patent.

Patented May 6, 1919.

Application filed June 27, 1917. Serial No. 177,219.

To all whom it may concern:

Be it known that I, THEODOR SULIKX, a citizen of the United States, residing at Barberton, in the county of Summit and State 5 of Ohio, have invented certain new and useful Improvements in Rotary Engines, of which the following is a specification.

This invention relates to rotary engines adapted for operation by motive fluid of 10 various kinds. It is particularly applicable to rotary engines of the type having a swinging abutment, and this abutment also serves to control the inlet of the motive fluid to the cylinder.

15 In the accompanying drawings—

Figure 1 is an end elevation of the engine;

Fig. 2 is an end elevation with the end plate removed;

20 Fig. 3 is a cross section showing the parts at the intake position;

Fig. 4 is a similar view with the parts at the exhaust position;

Fig. 5 is a section on the line 5—5 of 25 Fig. 4;

Fig. 6 is a section on the line 6—6 of Fig. 3;

Fig. 7 is a section on the line 7—7 of Fig. 3.

30 In the drawings, 1 indicates the cylinder in which the rotor 3 is mounted, and adjacent this cylinder is the abutment casing or extension 4 in which the abutment 5 is mounted. 6 is an end plate covering one 35 end of the cylinder, and 8 is a reinforcing rib for the periphery of the cylinder.

The rotor or piston 3 comprises a central hub 10 through which the drive shaft 12 extends. Extending outwardly from the 40 hub is the rim or body 13 of the rotor which is substantially T shaped in cross section. Grooves 14 are made in the sides of the rotor to receive the flange 15 or the bushing plates 16 which are held by the 45 screws 17, and packing rings 18 are placed in corresponding circular grooves in the bushing plates 16 which are inclosed within the end plates or cylinder covers.

The rotor 3 has two projecting wings 19 50 the front faces of which are tangent thereto as indicated at 21 and the rear faces of which are recessed as indicated at 20. These wings turn in contact with the cylinder wall.

The abutment 5 comprises an outer 55 knuckle 22 having trunnions 23 mounted in bearings 24 in the extension on the cylinder

referred to. Extending from this knuckle is a plate or part 25 which swings into and out of the cylinder and is provided with a roller 26 which rides on the face of the 60 rotor and its wings. The inlet pipe 41 is tapped into the projection on the casing and is adapted to communicate through a port 40 with a passage 33 in the abutment, said 65 passage leading to the space within the cylinder.

A screw 27 is provided to limit the inward swing of the abutment and to cushion the outward swing a pin 30 is provided which works in a recess 29 in the abutment 70 and is supported by a spring 31 under the head 32 of the pin and this head is adapted to strike the wall of the extension 4 when the abutment swings out.

The body of the extension 4 is bored 75 through as indicated at 34, and slotted as shown at 35 across the knuckle joint, giving sufficient spring to enable the wear on the bearing of the knuckle joint to be taken up by tightening the stud 36.

The bore or hole 29, in which the pin 30 works, communicates at its inner end with the intake passage 33, and when the pin is forced by the outward swing of the abutment its inner end crosses and closes the 85 passage 33, as shown in Fig. 4, and opens said passage when the abutment swings inwardly, which action is assisted by the spring 31.

In operation, with steam or the like the 90 fluid enters from the supply pipe 41 through the passage 33 when the parts are in the position shown in Fig. 3 and drives the rotor until the wing 19 lifts the abutment, thereby closing the passage 33 as shown in 95 Fig. 4. Exhaust takes place through the opening 42 in the cylinder wall and the operation continues.

The bushing plates 16 and rotor 3 are 100 cooled through openings 45 cut in the end plates 6 of the casing.

The invention thus provides a rotary engine capable of operation by steam, compressed air or other fluid and the swinging abutment acts to automatically control the 105 inlet of the motive fluid, without the necessity for any exterior valve mechanism.

I claim:

1. In a rotary engine, the combination 110 with a swinging abutment having a pivotal knuckle, of a casing forming a bearing for the knuckle and split at one side thereof,

and means to spring the parts together to contact with the wall of the casing, and a spring coiled around the pin, to cushion the outward swing of the abutment.

2. In a rotary engine, the combination with a cylinder casing and a rotor therein, of a swinging abutment pivoted in the wall of the casing and provided with an inlet passage, and an inlet port in the casing, adapted to be registered with said passage by the movement of the abutment, a pin 10 mounted in the abutment with one end in

In testimony whereof, I do affix my signature in presence of two witnesses.

THEODOR SULIKX.
